UNITED STATES PATENT OFFICE

JULES WERY, OF DEERFIELD, ILLINOIS; MAY WERY, ADMINISTRATRIX OF SAID JULES WERY, DECEASED, ASSIGNEE TO SAMUEL G. GORSLINE, OF RIVER FOREST, ILLINOIS

CAN-CLOSING MACHINE

Application filed August 15, 1928. Serial No. 299,771.

This invention relates to can-seaming or closing machines and it has among its objects the provision of a light, simple and efficient machine for automatically carrying out the entire sequence of operations necessary for producing a double seam or closure on cans of the type generally used in the trade.

The invention will be best understood from the following descriptions of the exemplifications thereof, reference being had to the accompanying drawings wherein

Fig. 1 is a side elevational view of a hand-operated machine embodying the invention,

Fig. 2 is a plan view of the machine, and

Fig. 3 is a developed view of the cam surface of the cam members used on the machine.

In Pat. No. 1,711,336 granted to me April 30, 1929 there is disclosed a double seaming machine of the hand operated type. The machine of said application comprises a supporting frame by means of which a can with a cover placed thereon is slowly rotated by means of a crank and the double seaming action is obtained by moving a pair of seaming rollers by means of a separate lever against the edge of the cover so as to first curl the edges of the cover and the can to an initial or preliminary position and then compress the same so as to secure a tight closure of the can.

In the foregoing machine the hand lever must first be moved in one direction and gradually pressed until it reaches a final position and then the hand lever must be moved in an opposite direction and gradually compressed until it reaches a second final position. The movement of the crank by means of which the can is rotated must be relatively fast as compared with the slow movement of the hand lever and the hand lever must always be held

sufficiently long in each of the two final positions until the can has been rotated several times with the seaming roller held in the final position. It is also important that the movement of the seaming levers toward the final positions shall be gradual in order to prevent

damaging or cutting of the can edges and in order to obtain a proper curl of said edge.

The machine of the present invention eliminates the use of a separate hand lever and secures automatic movement of the seaming rollers into seaming position in such a way as to obtain the most efficient seaming action. Furthermore, the machine is so arranged that at the end of one seaming operation the machine is ready to perform the next seaming operation so that one can can be closed immediately after the closing operation on another has been performed without any special resetting operations, rotation of the operating shaft in one direction being required throughout the entire sequence of the operations of the machine.

The invention will be explained by reference to an embodiment thereof in a hand-operated machine having a general appearance similar to that of the machine of my above-identified application.

Referring to the drawings, the machine comprises a U-shaped frame 11 having a cross member 12 and two upright posts 13 and 14. The lower portion of the frame 11 is provided with suitable U-shaped clamps 15 of familiar design by means of which the entire machine may be firmly clamped to a bench or the like. The frame with the clamps is preferably made of a single piece of metal by die-casting, for instance. On the cross member 12 of the frame is mounted the lifter plate 16 with the associated lifter mechanism comprising a lifter pin 17 longitudinally slidable in a perforated enlarged bearing member 18 of the frame and a circular lifter cam 19 freely slidable on the pin 17 and having an inclined cam surface 20 cooperating with a similar cam surface 21 on the upper end of the bearing 18. The cam 19 is provided with a cam lever 23 by means of which the cam 19 may be rotated around the pin 17, thereby causing the cam 19 to be forced upward along the inclined cam surfaces 20, 21. The upper end

of the pin 17 has a collar 25 by means of which the pin is held in place above the cam 19, washers 26 being interposed between the cam and the collar 25 to secure the correct spacing. One of these washers 26 is of a resilient cushioning material such as rubber to permit proper application of pressure to the can.

The lifter pin 17 terminates in a short stud 10 extending above the collar and fitting into a central perforation in the lifter plate 16 so as to hold the same in place. This lifter plate 16 is a substantially rigid disk-like member provided with a plurality of concentric grooves 16' for receiving the projecting edges of the lower closed ends of various sizes of cans that are to be seamed on the machine. The upper end of the upright 14 terminates into a threaded stud 35 and the upper end 15 of the upright 13 forms a U-shaped member terminating in a pair of studs 36. These studs fit into perforations on a transverse member 37 which completes the frame, the transverse member being firmly held in place 20 by means of nuts 38. The upper transverse frame member 37 is provided with a bearing 41 located directly above the lower bearing 18. In this upper bearing 41 is mounted a chuck spindle 42 having on its upper end 25 mounted a bevel gear 43 and carrying at its lower end a driving chuck plate 47. The driving chuck plate is arranged to be rotated by means of a pinion 51 engaging the bevel gear 43, the pinion being rotated by a shaft 30 52 journaled in upstanding lugs 53 of the upper transverse member. A crank 54 mounted on the right hand end of the shaft 35 serves to rotate the same.

The parts of the mechanism so far described are substantially identical with those described with somewhat more detail in my co-pending application referred to above with the exception of the construction of the upper end of the left-hand upright 13 which in the present case terminates into two studs 36 referred to above and the left-hand end of the transverse frame member 37 with the seaming mechanism mounted thereon that will now be described in detail.

50 The left-hand end of the upper transverse member 37 forms an enlarged supporting plate 61 provided with two bearing members 62 between which is journaled a shaft 63 of a worm wheel 64 adapted to be driven 55 by a worm 65 mounted on the extension of the main shaft 52 of the machine. The left hand of the shaft 52 is journaled in a bearing 66 carried on the left-hand end of the supporting plate 61. On pivot pins 70 and 60 71 secured on the right-hand edge of the supporting plate 61 on opposite sides of the center of the plane through the machine are mounted two seaming roll levers 72 and 73, the first lever carrying a preliminary seaming roll 74 and the second a finishing seaming

roller 75 such as described in my above identified application. The ends of the levers 72 and 73 opposite the seaming rollers are arranged to engage a pair of cam members 76 and 77 mounted on opposite sides of the worm wheel 64, the cam surfaces 76 and 77 being especially shaped and arranged to engage bearing rollers 78 on the seaming levers 72 and 73 so as to result in smooth action. The two cam levers 72 and 73 are pressed by means 75 of a spring 79 into engagement with a cam surface on the cam members 76 and 77.

Each of the cam members has a raised cam surface portion 81 so dimensioned that when said cam portion is in engagement with the bearing roller 78 on the associated seaming roll lever, the seaming roller mounted on said lever is pressed against the edge of the can and held in the final seaming position corresponding to the respective seaming roller. When the bearing roller 78 on the seaming roller levers is in engagement with the depressed portion of the cam member the seaming roller of the respective lever is out of engagement with the edge of the can cover. The raised portion of the cam surface is joined with the depressed portion by an inclined surface portion so shaped that when said inclined portion is pressed against the bearing roller of the respective seaming roller lever, the associated seaming roller will be gradually pressed into seaming position until it has reached its final seaming position corresponding to the flat raised portion of the cam surface, a developed view 100 of the cam surfaces on the two cam members being indicated diagrammatically in Fig. 3.

The raised portions 81 of the two cam members 76 and 77 are offset so that by continuously rotating the crank 54 the preliminary seaming roller 74 is first brought into action and upon termination of its seaming operation the second seaming roller 75 is brought into operation. After finishing the second seaming operation the worm wheel 64 is again in the same position as it was before the preliminary seaming operation was started so that the machine is ready to continue the next seaming operation after 115 inserting the next following can that is to be closed.

With the foregoing arrangement the seaming operations are carried out as follows: In order to start a seaming operation the machine is first brought into a position where the bearing rollers of the seaming roller levers 72 and 73 rest on the depressed portions of the cam surfaces so that the seaming rollers are out of engagement with the edges of the can that is to be seamed. Thereupon the can with the cover is placed in the machine and brought to the raised position by means of the lifter lever, as explained above. The crank 54 is now 139

rotated. This rotates the can and because of the gear reduction between the worm 65 and the worm wheel 64 it causes gradual rotation of the worm wheel 64. The rotation of the latter first swings gradually the seaming roller lever 72 outwardly as the bearing roller thereof comes into engagement with the raised portion of the cam member 76. This causes the preliminary seaming roller 74 to be gradually pressed against the edge of the can that is to be closed until the bearing roller 78 of the lever 72 has reached the flat upper raised portion of the cam member 76. This portion is of such length that the seaming roller 74 will be held pressed in its final position through several rotations of the can, preferably two or three full rotations.

The crank is continued to be rotated and in the course of this rotation the seaming roller lever 74 is released out of engagement with the edge of the can and the finishing seaming roller 75 is brought and held in engagement in the same way as a preliminary roller until the seaming roller operation has been performed and the can has been rotated two or three times in the final seaming position. The crank is continued to be rotated until the finishing seaming roller lever has been released from the cam edge, whereupon the closing operation is completed and the can may be taken out from the machine and the next can placed therein for performing the next closing operation.

My invention is not restricted to the precise details of construction and arrangements described hereinabove but many modifications will suggest themselves to those skilled in the art. It is accordingly desired that the invention be given a broad construction commensurate with the scope of the invention in the art.

I claim:

1. In a hand-portable can seaming machine, a frame comprising a base, a pair of spaced posts upwardly extending from said base and a cross member connecting the upper ends of said posts, a can holder mounted on said base, a chuck mounted on said cross member opposite said can holder for rotating a can held on said holder, a shaft on said cross member for rotating said chuck, a seaming roller supported on said frame, and a driving connection between said roller and said shaft for moving said roller into seaming position by rotation of said shaft.

2. In a hand-portable can seaming machine, a frame comprising a base, a pair of spaced posts upwardly extending from said base and a cross member connecting the upper ends of said posts, a can holder mounted on said base, a chuck mounted on said cross member opposite said can holder for rotating a can held on said holder, a shaft on said

cross member for rotating said chuck, a plurality of seaming rollers movably supported on said frame, and a driving connection between said seaming rollers and said shaft for alternately bringing said seaming rollers into seaming engagement with said can by the rotating action of said shaft.

3. In a hand-portable can seaming machine, a frame comprising a base, a pair of spaced posts upwardly extending from said base and a cross member connecting the upper ends of said posts, a can holder mounted on said base, a chuck mounted on said cross member opposite said can holder for rotating a can held on said holder, a shaft on said cross member for rotating said chuck, a plurality of seaming rollers for performing predetermined seaming operations, and a driving connection between said shaft and said seaming rollers, said driving connection being so arranged that upon continuous rotation of said shaft, said seaming rollers continuously repeat in sequence predetermined seaming operations involving the alternate steps of coming into seaming position and receding therefrom.

4. In a hand-portable can seaming machine, a frame comprising a base, means on said base for detachably clamping the same to a support, a pair of spaced posts upwardly extending from said base and a cross member connecting the top portions of said posts, a can holder mounted on said base, a chuck mounted on said cross member opposite said can holder for rotating a can placed between said can holder and said chuck, a shaft rotatively mounted on said cross member in the direction from one post to the other, a driving connection between said chuck and said shaft for imparting rotary movement to said chuck upon rotation of said shaft, a pair of seaming roller levers movably associated with said cross member, a preliminary seaming roller mounted on one of said levers, a finishing roller mounted on the other of said levers, and cam means mounted on said cross member in driving engagement with said shaft and said levers to cause said rollers to be alternately brought into seaming position against said chuck upon continuous rotation of said shaft.

5. In a hand-portable can seaming machine, a frame comprising a base, a pair of spaced posts upwardly extending from said base and a cross member connecting said posts, a can holder mounted on said base between said posts, a chuck rotatively mounted on said cross member opposite said can holder, a shaft extending longitudinally between said posts and rotatively mounted on said cross member, a driving connection between said chuck and said shaft for imparting rotary movement to said chuck by the rotary movement of said shaft, a pair of seaming roller supports mounted on opposite sides of said frame

for movement into seaming position against said chuck and into receded position away therefrom, a seaming roller on each of said supports, a cam member rotatively mounted between said roller supports for engagement with said shaft to be rotated thereby, and means for providing a driving engagement between said roller supports and said cam member for alternately bringing said seaming rollers into seaming position upon continuous rotation of said shaft.

6. In a can seaming machine, a frame, a driving shaft mounted on said frame, a chuck journaled on said frame in the direction transverse to said shaft underneath the same, a gear driving connection between said shaft and said chuck, a rotary gear member geared to said shaft and disposed in the plane of said shaft and said chuck axis, cam surfaces on the opposite sides of said rotary gear member, levers pivotally mounted on opposite sides of said shaft for driving engagement with said cam surfaces, and a seaming roller on each of said levers arranged to be moved by the driving action of said cam surfaces into seaming position against said chuck, the cam surfaces on the opposite sides of said rotary gear member being so arranged as to alternately bring said seaming rollers into seaming position against said chuck.

7. In a hand-portable can seaming machine, a frame comprising a base, clamping means for detachably clamping said frame to a support, a standard upwardly extending from said base, and a cross-member on said standard, a can holder mounted on said base, a chuck rotatively mounted on said cross-member opposite said can holder, a pair of seaming roller supports mounted on said frame, a seaming roller on each of said supports, cam means rotatably mounted on said frame for independently actuating each of said seaming roller supports to alternately bring said seaming rollers into seaming position against said chuck, a driving shaft on said cross-member, a gear connection between said shaft and said chuck, and a gear connection between said cam means and said shaft, said gear connections being so arranged that upon continuous rotation of said shaft, a rotary movement is imparted to said chuck, and said seaming rollers are alternately brought into seaming position against said chuck.

8. In a hand-portable can seaming machine, a frame comprising a base, clamping means for detachably clamping said base to a support, a standard upwardly extending from said base, a cross-member on the upper end of said standard, a can holder mounted on said base, a chuck mounted on said cross-member opposite said can holder for rotating a can held in said holder, a shaft mounted on said cross-member, a gear connection between said shaft and said chuck for rotating said

chuck to drive a can held on said holder, a plurality of seaming rollers supported on said frame, and a gear drive between said rollers and said shaft for alternately bringing said rollers into seaming engagement against said chuck by the rotating action of said shaft.

In testimony whereof I have hereunto subscribed my name this 10th day of August, 1928.

JULES WERY.
